UNITED STATES PATENT OFFICE.

HOWARD F. SMITH, OF HOUSTON, TEXAS.

PIPE-ROTATING ATTACHMENT FOR ROTARIES.

Application filed March 12, 1923. Serial No. 624,590.

To all whom it may concern:

Be it known that I, HOWARD F. SMITH, citizen of the United States, residing at Houston, in the county of Harris and State 5 of Texas, have invented certain new and useful Improvements in Pipe-Rotating Attachments for Rotaries, of which the following is a specification.

This invention relates to new and useful 10 improvements in a pipe rotating attachment for rotaries.

One object of the invention is to provide an attachment of the character described embodying the combination with a tong for 15 gripping the pipe to be turned of an improved type of back up post designed to be mounted upon a rotary through which the back up post is revolved, and the tong thereby rotated to turn pipe to which the 20 tong is applied.

Another object of the invention is to provide an improved type of back up post which may be easily released from the tong to 25 permit the release of the latter from the pipe.

A still further feature of the invention resides in the provision of a combined apparatus including a back up post and a pipe 30 rotating tong, and means whereby the latter is sustained in position relative to the former so that the tong will be sustained in position above the rotary table for convenient 35 application of, or release from the pipe to be turned.

With the above and other objects in view the invention has particular relation to certain novel features of construction, operation, and arrangement of parts, an example 40 of which is given in this specification and illustrated in the accompanying drawings, wherein:—

Figure 1 shows a plan view of the tong as applied to the pipe.

Figure 2 shows an edge view thereof.

Figure 3 shows a side elevation of the back up post.

Figure 4 shows a plan view thereof.

Figure 5 shows a transverse sectional view taken on the line 5—5 of Figure 3.

Figure 6 shows a transverse sectional view taken on the line 6—6 of Figure 4 and,

Figure 7 shows a fragmentary side view of the back up post and the tong sustaining means carried thereby.

55 In the drawings the numeral 1 designates the pipe to be rotated. The numeral 2 des-

ignates the tong handle to one end of which the arcuate jaw 3 is pivoted at one end. To the other end of this jaw there is pivoted the arcuate jaw 4, and to the free end of this last mentioned jaw there is pivoted a U-shaped latch 5 which is designed to be engaged over the outwardly turned lug 6 of the inner end of the handle 2. When the latch is engaged and pressure applied to the handle in the direction indicated by the arrow in Figure 1 the combined action of the handle on the jaw 3, and the lug 6 on the jaw 4 through the latch 5, will cause said jaws to grip pipe and turn the pipe and the jaws 7 are provided with pipe engaging teeth 7 which insure the engagement of the jaws with the pipe. The handle 2, when the tong is in action will stand in substantially a tangential position relative to the pipe 1, and in this position when pressure is applied to said handle it will operate to exert a pull, through the lug 6 and the link 5 on the jaw 4 and at the same time will force the jaw 3, to which it is pivoted inwardly toward 80 said pipe so as to accomplish the effective gripping of the pipe by said jaws. The numeral 8 designates a back up post whose lower end 9 is reduced and fitted into a suitable socket provided in the top of the rotary table. Rotary tables for drilling wells by the well known rotary process are in common use and their construction is well known to those skilled in the art of well drilling, and at the present time these rotary tables are commonly provided with a socket to receive the back up post. Near 85 its upper end the post 8 is provided with a table 10 preferably circular in form and arranged eccentric with respect to the post 90 and rotatably mounted on the upper end of said post and resting on said table there is an eccentric 11 preferably circular in form which has a surrounding band 12 seated in a counter sunk groove in the periphery of 95 the eccentric. Said band has the spaced lugs 13, 13 provided to embrace the ear 2' carried by the tong handle 2 and having the aligned oblong slots 14 to receive the pin 15 carried by the ear 2', and through 100 which the said handle is connected to the eccentric 11, said slots 14 permitting a certain freedom of movement between these connecting parts. Fastened to the eccentric 11 there is a suitable handle 16 by means of 105 which the eccentric may be rotated into coinciding position with the table 10 or into

eccentric position relative thereto, the latter position being shown in Figures 3 and 4. The upper face of the table 10 has an eccentric groove 17 and depending from the eccentric there is a stud 18 adapted to ride in said groove and when the eccentric 11 is manipulated into eccentric position relative to the table, said stud 18 contacts against a stop 19 formed on the periphery of the table to limit the range of the movement of the eccentric.

Near the lower end of the post 8 it is formed with a comparatively wide base 20 to which there is secured a tong support 21 which may or may not be flexible as desired and to the upper end of this support 21 the tong is attached and by it the tong is supported in position above the rotary table so as to be in position for easy engagement with, or release from, the pipe.

As before stated the pipe is rotated in the process of screwing together and unscrewing joints thereof in making up or breaking up the drill stem by the rotary table through said back up post, and when in operation the eccentric 11 is turned into eccentric position relative to the table 10 as illustrated in Figures 3 and 4. Great force is required in screwing together and unscrewing the joints of pipe, and when some types of back up posts are used it is very hard to release the tong therefrom on account of the pressure of the post against the tong. When the type of back up post herein described is used and it is desired to release it from the tong handle the handle 16 may be grasped and turned in the direction indicated by the arrow in Figure 4, and this will operate to swing the eccentric back toward coinciding position with the table 10 and will operate to release its pressure against the tong handle permitting the release of the latch 5 and the consequent release of the tong from the pipe 1. When the tong has been released from the pipe the handle 16 may then be manipulated in the opposite direction until the stud 18 contacts against the stop 19 and may then be rotated further thus rotating

the entire post 8 in the rotary table socket and the tong will thus be bodily swung 50 around away from the pipe and out of the way so as not to interfere with the other drilling process until it is desired to again use said tong.

What I claim is:—

1. In combination a tong, a back up post, a support through which the tong is supported in relation to the back up post, an eccentric mounted on said back up post and connected to the tong, means for rotating 60 said eccentric relative to the post through a limited range of movement, and interlocking means carried by the eccentric and post respectively through which the further rotation of the eccentric will operate to rotate 65 the post.

2. In a device of the character described, a back up post, an eccentric mounted thereon, means for rotating said eccentric through a limited range of movement relative to said post, and interlocking means carried by the eccentric and post respectively through which the post is rotated with the eccentric when the latter is further rotated through said means.

3. In a device of the character described, a back up post, a table carried thereby, an eccentric rotatably mounted on said post and resting on said table, and means for rotating said eccentric.

4. In combination a tong whose handle is provided with a lateral ear, a back up post, a support connected to the back up post and the tong, and supporting the latter, an eccentric mounted on said post and connected to said ear, and means for rotating the eccentric.

5. In combination a tong, a back up post, a support connected to the back up post and supporting the tong, an eccentric mounted on said post, means connecting said eccentric to the tong handle, and means for rotating the eccentric.

In testimony whereof I have signed my name to this specification.

HOWARD F. SMITH.
